UNITED STATES PATENT OFFICE.

WILLIAM I. MARABLE, OF MONROE, GEORGIA.

ALARM.

1,116,600.

Specification of Letters Patent. Patented Nov. 10, 1914.

Application filed June 10, 1914. Serial No. 844,375.

To all whom it may concern:

Be it known that I, WILLIAM I. MARABLE, a citizen of the United States, residing at Monroe, in the county of Walton and State of Georgia, have invented certain new and useful Improvements in Alarms, of which the following is a specification, reference being had to the accompanying drawings.

This invention relates to new and useful improvements in burglar alarms and more particularly to a spring actuated alarm, the main object of the present invention being the provision of a burglar alarm adapted for application to a window or door casing to be actuated upon the opening movement of the window or door and thus notify the occupants of the building of the entrance of unauthorized persons.

Another object of the present invention is the provision of a device of this character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claims.

In the accompanying drawing forming a part of this application, Figure 1 is an elevation of an alarm constructed in accordance with my invention, parts thereof being broken away. Fig. 2 is a top plan view of the locking member, illustrating the same in its effective position. Fig. 3 is a side elevation of the locking member; and Fig. 4 is a detail perspective view of the keeper applied to the window to retain the engaging block in its effective position.

Referring more particularly to the drawings, 1 indicates a window casing and 2 the slideable sash therein. The sash 2 is provided with a catch member 3 which is adapted to engage with a shoulder 4 formed in the window casing and prevent the window frame from being raised beyond a certain extent.

Arranged upon one side of the window casing, is my improved alarm which is generally indicated by the numeral 5 and which is preferably inclosed within a suitable casing 6. The main body of the alarm includes the clock-work mechanism which is indicated by the numeral 7 and which may be of

any general or well known type arranged between the two spaced supporting plates 8, said plates being securely held in position by means of the usual transverse bolts 9. Slidably mounted upon one of the plates 8, is an elongated plate 10 which is provided with the grooves 11 in which the guide members 12 are arranged to prevent the lateral movement of the plate 10 after once being placed in position.

Formed upon the inner end of the plate 10 is an outwardly projecting lug 13 which is adapted to engage with the gear 14 to cut off the mechanism when desired. This plate 10 is actuated by means of a rod 15 on the outer end of which is secured a thumb piece 16 adapted to be braced by the forefinger or thumb to reciprocate the same and engage the lug 13 with the gear 14. It will be noted that the lug 13 normally engages the gear 14 so that upon the upward movement of the window sash 2, the same will be disengaged by having the block 17 engaged with the inner end of the plate 10, forcing the same longitudinally within the body 5 and disengaging the lug 13 from the gear 14 to permit the bell 18 to ring. It will be noted that the block 17 is provided upon one side with a cam surface 19 adapted to be engaged by the rounded outer end of the plate 10, so that the plate may be readily reciprocated. The block 17 is secured to a movable plate 20, the lower end of which is pivoted, as shown at 21 to the sash 2, while the other end thereof is bent upwardly to form a finger-piece 22 and said plate is arranged between the lugs 23 at a point adjacent the outer end thereof, said lugs being formed upon the opposite ends of a plate 24.

From the above description taken in connection with the accompanying drawing, it will be readily apparent that I have provided a simple and durable burglar alarm whereby should an attempt be made to enter a dwelling or other building by raising the sash 2, the occupants of the building will be notified in view of the fact that the cam surface 19 of the block 17 will engage the outer rounded end of the plate 10 and force the same longitudinally, so as to disengage the lug 13 from the gear 14 and allow the bell to ring. It will also be apparent that my device is extremely simple in construction and can be readily placed upon doors, windows or any other suitable place, whereby entrance may be gained to the building. The device,

can be manufactured and placed upon the market at a comparatively low cost.

In the operation of my improved alarm, it will be noted that when the window is raised, the catch member 3 will slide upwardly until it engages the shoulder 4, thus further upward movement of the window will throw the same toward the right hand side of the frame, so as to positively engage the block 17 with the inner end of the elongated plate 10 and force the same laterally with respect to the window, in order to disengage the lug 13 from the gear 14. From this it will be apparent that when an attempt is made to raise the window by an outside person, the engagement of the catch member 3 with the shoulder 4 will positively engage the block 7 with the plate 10, thus unlocking the gear and permitting the bell to ring. It will also be apparent that when the device is not in use, the block 7 will be swung outwardly, as indicated in dotted lines in Fig. 1, so that the window may be raised or lowered, without interfering with the alarm.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I claim is:

1. A device of the class described including in combination with a window casing and sash, of a bell mounted on the casing, mechanism for actuating said bell, locking means adapted to normally engage the actuating mechanism, a cam member carried by the window sash and adapted to engage said locking means to release the actuating mechanism, and means carried by the win-

dow sash for engagement with the casing, whereby to positively force the cam into engagement with the locking mechanism, as and for the purpose set forth.

2. A device of the class described including a window casing and sash, a bell carried by the casing, actuating mechanism for said bell, a sliding plate adapted for engagement with portions of the actuating mechanism to retain the same against movement, a pivoted plate carried by the window sash, spaced lugs adapted to be arranged upon opposite sides of one end of the plate to retain the same in its effective position, a cam member carried by said plate adapted to engage the inner end of the locking plate upon the upward movement of the sash to release the actuating mechanism, and means carried by the sash adapted for engagement with the casing, whereby to positively engage the cam with the locking plate.

3. A device of the class described including a window casing and sliding sash, a bell carried by the casing, actuating mechanism for said bell, a sliding plate adapted for engagement with a portion of the actuating mechanism to retain the same against movement, a pivoted plate carried by the sash, a cam member carried by the plate adapted to engage the inner end of the sliding plate upon upward movement of the sash to move said plate in one direction and release the actuating mechanism, a pivoted catch member carried by the sash, a shoulder formed on the casing and adapted to be engaged by the catch whereby to positively engage the cam member with the inner end of the locking plate, as and for the purpose set forth.

In testimony whereof I hereunto affix my signature in the presence of two witnesses.

WILLIAM I. MARABLE.
